(57) **CLAIM**

The ornamental design for product packaging, as shown and described.

DESCRIPTION

FIG. 1 is a right-frontal perspective view of product packaging showing our new design according to a first embodiment;

FIG. 2 is a right-side elevation view thereof;

FIG. 3 is a left-side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a right-frontal perspective view thereof illustrated with a product positioned thereon, where the product is illustrated as obstructing a portion of the product packaging; FIG. 9 is a right-frontal perspective view of product packaging showing our new design according to a second embodiment;

FIG. 10 is a right-side elevation view thereof;

FIG. 11 is a left-side elevation view thereof;

FIG. 12 is a rear elevation view thereof;

FIG. 13 is a front elevation view thereof;

FIG. 14 is a top plan view thereof;

FIG. 15 is a bottom plan view thereof; and,

FIG. 16 is a right-frontal perspective view thereof illustrated with a product positioned thereon, where the product is illustrated as obstructing a portion of the product packaging. The dot-dash lines define the bounds of the claimed design and form no part of the claimed design, and the dashed lines are for the purposes of illustrating portions of the product packaging that form no part of the claimed design.

1 Claim, 10 Drawing Sheets
